UNITED STATES PATENT OFFICE.

WALDO A. LAYMAN AND FERDINAND SCHWEDTMANN, OF ST. LOUIS,
MISSOURI.

MEANS FOR REGULATING CONSTANT-POTENTIAL TRANSFORMERS.

SPECIFICATION forming part of Letters Patent No. 635,786, dated October 31, 1899.

Application filed February 27, 1899. Serial No. 707,073. (No model.)

To all whom it may concern:

Be it known that we, WALDO A. LAYMAN and FERDINAND SCHWEDTMANN, citizens of the United States, residing at the city of St. Louis, State of Missouri, have invented a certain new and useful improvement in means for deriving and maintaining a constant alternating current in a circuit of varying resistance from the windings of a constant-potential transformer, of which the following is a full, clear, and exact description, such as will enable others skilled in the art to which it appertains to make and use the same, reference being had to the accompanying drawings, forming part of this specification, in which—

Figure 1 is a diagrammatic view illustrating our improved means for deriving and maintaining a constant alternating current in a circuit of varying resistance from the windings of a constant-potential transformer. Fig. 1^a is a plan view of a mutilated gear used in connection with our improved switch. Fig. 1^b is a detail view illustrating the means for engaging the teeth of said mutilated gear with its driving-pinion after said pinion has been rotating idly in the mutilated section of said gear and then reversing its direction of rotation. Fig. 2 is a diagrammatic view of a modification thereof. Fig. 3 is a diagrammatic view of another modification of the system for cutting in and cutting out coils of the transformer-winding.

This invention relates to a new and useful improvement in means for deriving and maintaining a constant alternating current in a circuit of varying resistance from the windings of a constant-potential transformer which is fed from a constant-potential dynamo.

The invention is designed particularly for use in connection with the operation of alternating-current arc-lamps which are arranged in series from the secondary of the transformer. It will be obvious that there are other uses to which our invention can be put without in the least departing from the nature and principle of the same.

Heretofore arc-lamps have been operated with alternating currents in various ways.

We will refer to a few of these methods for

the purpose of distinguishing our present invention therefrom.

The first application of alternating currents to arc-lighting systems to which we will refer is that known as the "constant-potential multiple" system. By this system lamps operating as individual units were run in parallel between low-tension feeders in the same way as incandescent lamps are now generally used where such incandescent lamps are used for commercial lighting. The amount of current taken by each arc-lamp in this system is regulated by mechanism located inside of the lamp itself or by this mechanism in conjunction with auxiliary resistance or reactance, and the general practice is to supply to the circuit a constant potential. Where these lamps are not fed from a low-potential circuit, it is necessary to introduce a step-down constant-potential transformer between a set of high-tension circuit-wires. The high-tension wires above referred to take the place of the low-tension circuit, and in this event the general plan of operation is the same, with the exception that the lamp is supplied with the proper energy required by the interposition of a reduction-transformer between the lamp and the circuit.

Another system is the arrangement of the arc-lamps in series, the circuit containing these lamps being fed from the secondary of a constant-potential transformer fed by a constant-potential dynamo. In this arrangement the control of current flowing in the circuit is effected by means of regulating resistance or inductances in either the primary or secondary circuits. As is well known, the condition of an arc-lighting series circuit is a very unstable one, many causes entering to make the effective resistance of the circuit a widely-varying quantity. By reason of this wide variation in the resistance of this circuit the variation of the current (providing that the potential supply is constant) is as great as is the variation of the resistance. The successful operation of the circuit, however, is dependent on the maintenance of the current flowing at a constant value. Manual regulation of the switchboard is therefore resorted to to procure this constant value, which re-

quires the attention of a skilled electrician, whose duties are to plug in or plug out, as the circuit demands. The circuit being thus dependent upon the strict attention to duty on the part of the attendant, it will be seen that very wide irregularities in the operation of the circuit might easily arise. Further than this, serious consequences might follow from these variations in that the partial or possibly the total destruction by burning out might result not only to the lamps but to the transformer feeding the circuit, with the further objectionable result of a very wide variation of the current demand upon the dynamo. These variations are sometimes so sudden and of such wide range as to render the manual manipulation of the switchboard impossible with respect to the control thereof by the attendant within safe points. Another system for the use of alternating arc-lamps in series makes use of what is known as a "constant-current transformer," operating on a constant-potential circuit. This transformer is so constructed as to furnish a constant secondary current through the medium of the automatic introduction of a large magnetic leakage in the transformer—that is, the transformer is so constructed as to limit the amount of magnetic lines of force which will effectively thread themselves through the secondary circuit. Transformers may be constructed to accomplish this end in several ways, and it is not deemed necessary to explain the same here, and such transformers can, if built properly, effectually maintain practically constant current in the lamp-circuit within wide limits. In doing this they answer the practical requirements, and did they not involve certain objectionable features outside of the lamp-circuit would be a very satisfactory solution of the problem. We will refer to a few of the important objections to this system:

First. The so-called "power factor" of the current which such a transformer as this draws from the dynamo is low at practically all times, decreasing in value with the amount of magnetic leakage. It is at its best value when the arc-circuit feeding from the secondary is operative under normal conditions, for which this immediate system was designed. Should for any reason the resistance of the arc-circuit fall below the normal value, the consequence will be an increase of the magnetic leakage in the transformer and a consequent decrease of the power factor of the current supplied by the dynamo. It is detrimental to the satisfactory pressure regulation of an alternating dynamo to have a current of low power factor taken from the dynamo in so far as the dynamo is concerned, chiefly by the fact that it becomes difficult to maintain a constant pressure at the brushes, and, further, that the capacity of an average alternating-current dynamo is very much decreased under such conditions. In other words, it is possible to operate an alternating-

current dynamo in extreme cases with fifty per cent. more load when the power factor is high than can be accomplished when the power factor is low, and therefore it is of great advantage to the central stations to have the power factor of their service as high as possible. If the pressure regulation of the dynamo is poor by reason of a variable and low power factor of the current taken from it, it becomes disadvantageous to operate incandescent lamps from the same dynamo, as it is well known that incandescent lamps operate efficiently and with long life only when the pressure of the current subjected to them is maintained practically constant.

Second. The ratio of current in the primary winding in the transformer to the current in the secondary winding of the transformer remains practically constant regardless of the condition of the arc-light circuit external of the transformer—that is, it matters not as to the amount of current flowing through the windings of the transformer whether there be one-half or all of the lamps of the arc-circuit in effective operation. The result of this feature of the transformer is that the waste of energy in the copper windings thereof is practically a constant quantity regardless of the amount of effective work which is being done in the external secondary circuit thereof, and therefore the energy losses in the transformer are practically constant at all times. The fact that there exists in such a transformer the feature of the amount of current being always constant contributes to the increased reaction upon the dynamo itself—that is, the effect of the decrease of power factor of the current taken from the dynamo upon the regulation of the dynamo is worse when little work is being done in the arc-light circuits than when a great amount of work is being done. If a small amount of work were done in the circuit and the amount of current taken from the dynamo were decreased proportionately, the effect on the dynamo would not be so serious even did the power factor of the lessened current decrease. As it is, however, there is the double effect of the current demand remaining large when the work being done is small and the power factor decreasing with the same amount of current when the work being done is small.

In our system the power factor remains constant at practically all loads and at a high value, while the demand of current from the dynamo bears an almost constant ratio to the amount of work being done in the arc-light circuit.

Another system has made use of a constant-potential transformer with an external resistance or reactance automatically governed. Where resistance is used, a high power factor is always maintained; but the loss, or rather the power consumed by the system, is always the maximum energy required for the whole circuit—that is, if the effective circuit of arc-lamps does not require the maximum energy

by reason of several lamps being temporarily or otherwise removed from the circuit the energy which these removed lamps from the circuit require is taken up in the auxiliary resistance. Such a system is highly inefficient. Where a reactance is inserted, it accomplishes practically the same thing within the transformer and with all the attendant objectionable features of a constant-current transformer above referred to.

Our invention therefore consists in the use of a constant-potential transformer, the winding thereof being built in steps. We introduce automatically-controlled regulating de-

vices which vary the amount of winding of the transformer in actual use in proportion to the requirements of the circuit. This automatic controlling device is so arranged that the current which flows in the winding of any

and all such portions in actual use will be maintained practically (so far as the secondary is concerned) constant, being the amount required for the operation of the external arc-lighting circuit or other circuit. It is well

known that a constant-potential transformer gives out from its secondary in energy the same amount within a small per cent. as is supplied to the primary in energy. The amount of energy, real or apparent, in either

primary or secondary circuit is proportionate to the product of the pressure of the current in both cases. It is our intention to take from the secondary a constant current, and therefore the amount of energy which we draw

from the secondary will be proportionate to the pressure which we require to use, and the amount of such pressure will be immediately in proportion to the number of steps of the secondary winding of which we make effect-

ive use. The total demand of energy from the dynamo will thereby be proportioned to the amount of pressure which we take from the secondary circuit. Since the secondary current is constant and since the primary pres-

sure is constant, it follows that the amount of current which we take from the dynamo will be proportionate to the amount of pressure made use of on the secondary side of the transformer. It is well known that a trans-

former constructed for a constant-pressure reduction is one in which the power factor of the current in the primary circuit is practically the same as the power factor of the current in its secondary circuit. This be-

ing the case, the power factor of the current-supply taken from the dynamo will with our arrangement be the power factor of the current flowing in the arc-lighting circuit. It is also well known that the power factor of

an arc-lamp where inductances or reaction-coils are not introduced is relatively high, being approximately .85 to .90. If we introduce no auxiliary reactance-coil or other form of auxiliary resistance devices, the power

factor of the current taken from our transformer will be practically .85 to .90, and therefore the power factor of the current taken

from the dynamo will be substantially the same—that is, .85 to .90—and will be practically constant for all conditions of resistance in the secondary circuit, since the only variation of resistance in the arc-lighting circuit will arise from the cutting in or cutting out of lamps.

To sum up briefly the advantages accomplished by the use of our system, we may recapitulate as follows:

First. The current drawn from the dynamo always has a high power factor and is in proportion to the number of lamps burning in the arc-circuit.

Second. The arc-circuit is at its maximum efficiency if we introduce no resistance to take the place of lamps which temporarily or otherwise are cut out of the circuit.

Third. The transformer is at its maximum efficiency as the losses therein are in a measure proportionate to the effective work being done in the circuit.

In the accompanying drawings, to which we will now refer as illustrating several ways of carrying out our improved system, we have shown a well-known construction of switch, to which we lay no claim in this present application, and while we have illustrated a lamp-circuit in said drawings we do not wish to be understood as limiting the application of our system or proposed arrangement of devices to arc-lighting circuits alone, as it is obvious that there are other kinds of service in which the same conditions exist in which our system can be used with good effect. In fact, any circuit where a constant current is required and a variable resistance is met can be with equal effectiveness operated from a constant-potential transformer by our method, it being automatically controlled by the current flowing, the apparatus effectually protecting itself from damage of any sort, such as burning out or otherwise.

In Fig. 1 of the drawings, T indicates a transformer between the dynamo and lighting-circuit. A constant potential is applied to the primary winding P, developing practically a constant potential in the secondary winding S. This secondary winding is so wound that taps are brought out at intermediate points between the first and last ends, as at 0, 1, 2, 3, 4, 5, 6, 7, and 8. These intermediate points (indicated by the taps 0 to 8, inclusive) are connected to terminals or corresponding points on a switchboard A, said terminals being in Fig. 1 preferably arranged concentrically to the axis of rotation of a switch-arm B. This switch-arm carries two contact-points b and b', coöperating with the terminals of the taps and so arranged with relation to each other and to said terminals that at least one of said contacts is in engagement with a terminal. Contacts b and b' coöperate at their inner ends with rings c and c', from which lead wires to an impedance-coil I, tapped at its center by the supply-wires of the lamp-circuit. Switch-arm B has con-

joined to it a beveled gear C, with which meshes a pinion D, rigidly mounted on shaft E, supported in suitable bearings. Shaft E carries a friction-roller F at its other end, which roller bears upon a disk-plate G, revolvably mounted in an arm H, suspended from the armature-shaft of a small motor M or other source of power, so that said disk will be constantly rotated at an even rate of speed. In the construction shown in Fig. 1 disk G is driven by a belt running over a pulley on the armature-shaft, and the motor is supplied with energy from the primary circuit, although it is obvious that the motor can be a direct-current motor and supplied from such a source of energy. Arm H, carrying disk G, is designed to be swung upon its pivotal support, as indicated by dotted lines, and to effect this lateral position of said disk we arrange cables R on each side of support H, which cables, at their opposite ends, are connected to plungers n and o of the solenoids N and O. The solenoid O receives its current from either the secondary or primary winding of the transformer, and when the transformer is in operative connection with the dynamo-circuit the magnetic strength of solenoid O is practically constant. We may, if we desire, utilize a step-down transformer T', whose secondary is in series with the solenoid O. For the sake of distinction we will call the circuit in which the solenoid is arranged an "auxiliary circuit of constant potential," regardless of the source from which it is derived. The solenoid N is in series with the arc-lamp circuit, and therefore its magnetic strength depends on the amount of current flowing in this circuit. For the sake of distinction we will call the circuit in which the solenoid N is arranged a "circuit of varying potential with constant current." We provide the plunger n to co-operate with this solenoid with a spring L.

In operating the system it is intended and desired that the combined strength of solenoid N and the spring attached to its plunger shall exactly equalize the strength of the plunger in solenoid O when the lamp-circuit receives the proper amount of current. Should the strength of N and L decrease, the plunger o will be drawn farther out, which swings the disk G to one side, so as to rotate the switch-arm B in such direction as to cause said switch to increase the total pressure between points 40 and 50 of the arc-lamp circuit until the current in the solenoid N and the lamp-circuit runs up to such strength as to enable the solenoid N to draw the disk G back to its central position, where equilibrium is established. Should solenoid N become too strong, its plunger is drawn down and the reverse rotation of the switch-arm B follows, cutting down the pressure between 40 and 50. As shown in Fig. 1, we prefer to arrange impedance or choking coils around each lamp in the circuit which are in shunt or in parallel with the lamp, so that should a lamp be temporarily extinguished it will not affect the

operation of the remaining lamps in the system. Should a break in the circuit occur, say, at 45, this would run the pressure up between 40 and 50 to the full capacity of the transformer, and the solenoids would automatically adjust themselves to such changed conditions and operate the switch which controls the secondary circuit of said transformer according to the position of the terminals of its taps or steps.

A short-circuit in the system is another contingency which is taken care of by our improved arrangement. Were no protecting devices introduced into the system, a short-circuit would reduce the pressure between 40 and 50 to zero, in which event the solenoid O would operate to turn the switch to its zero position or position of starting, as shown in Fig. 1. A third condition which would also be taken care of by our improved system would be when the transformer is cut out of circuit, rendering both opposing solenoids ineffective. Under such circumstances the spring L operates to return the switch-arm to zero for the next start.

It will be seen from the above that the secondary of our constant-potential transformer is stepped, each lead-out or step having a terminal in the path of a switch; that said switch is automatically controlled to contact with various terminals, according to the condition of the secondary circuit; that such controlling means comprise opposing solenoids—one in the lamp-circuit and the other fed from the secondary or primary circuit proper—said solenoids being so influenced under certain circumstances as to throw into or out of operative position certain mechanical devices to operate said switch in either direction or to cause said switch to assume a stationary position; that independent of this automatic control during the period in which the system is operating means are also provided acting independently of the system for automatically restoring the system to a normal position in readiness for another start.

In the event that the pressure in the secondary circuit is run up to the full capacity of said secondary the segment or gear with which the pinion meshes is carried around until its last tooth passes the pinion, when the switch-arm rests on the terminal marked 8, being the full capacity of the machine, and is there held. If for any reason the pressure in the secondary circuit is still insufficient to bring the secondary circuit to the normal amount, the switch can be turned no farther, as the gear C, as shown in Fig. 1^a, is provided with a blank portion—that is, a few teeth are removed to mutilate said gear—and when the pinion D reaches said mutilated portion it will rotate idly. The pinion reaches this mutilated portion when the switch-arm is at its extreme limits, as when resting on terminals 0 and 8. (Shown in Fig. 1.) The stop b^x is provided on the lower face of arm B, as shown in Fig. 1^b, and this stop co-oper-

ates with springs x and x' , projecting from each side of a stud a , arranged on the switch-board, as shown. When the external circuit is cut out or for any reason the pressure is 5 reduced therein, the spring x , which is normally in engagement with the projection b^x when the switch-arm coöperates with the terminal 8 in its normal position and the pinion rotates idly in the mutilated portion of the 10 gear, causes the switch-arm to move toward 7, which turns the mutilated gear, so that the same will instantly engage with the pinion and starts on its backward rotation until equilibrium is restored in the system and the 15 switch-arm brought to a stationary position, when it can be again moved the full capacity of the secondary, as before described. If, however, the movement of the switch-arm continues until it reaches the zero position, 20 it will be arrested by the engagement of the projection b^x with the spring x , at which time the mutilation in the gear will be in register with the pinion, and the pinion will operate idly. Spring x' now exerts its energy to engage 25 the mutilated gear with the pinion immediately that the secondary is cut in, so that the solenoids will be energized to reverse the rotation of the pinion. This operation will be readily understood when it is borne in 30 mind that the disk operates the pinion in opposite directions, depending upon the preponderance of energy in the respective solenoids, and the pinion, being in engagement with the gear, will rotate the same until the 35 mutilated portion of the gear is reached, when the pinion, if rotation thereof continues, will rotate idly, merely slipping over the last tooth it had previously engaged. The springs x and x' , when the switch-arm is in either of its 40 extreme positions, tend to force said switch-arm in such direction that the tooth last engaged by the pinion will be in readiness to again engage the pinion immediately that the pinion commences its backward rotation. 45 The above conditions prevail with respect to the construction shown in Fig. 1 of the drawings; but it may be desirable at times to run the capacity of the secondary even higher by reducing the number of windings of the 50 primary after the secondary has reached its full capacity, and to accomplish this we provide terminals 9, 10, and 11 in the path of the switch-arm B , as shown in Fig. 2, which are engaged by switch-tongues b'' and b''' , which 55 switch-tongues engage at their inner ends with concentrically-arranged rings c'' and c''' , both of which form terminals for the return-wire of the dynamo-circuit and are connected with an impedance-coil I' in substantially the 60 same manner as the impedance-coil I . It is obvious by this arrangement that the secondary should be kept in circuit while the primary is being cut down, and this is accomplished by extending the terminal 5 the full 65 distance of the movement of the switch-arm, and, further, as the primary must be kept in circuit while the secondary is cut in the first

terminal of the primary with which the switch-arm engages is continuous and coöperates with the switch-arm until the separate terminals of the secondary are passed, when the separate terminals of the primary are then in readiness for individual coöperation with the switch-arm. 70

It is obvious that while we have shown and described separate operations for cutting in and cutting out the secondary and primary windings in succession they could be cut in and cut out contemporaneously or alternately and accomplish the same result. 75

Impedance-coils I and I' act merely as choking-coils for the purpose of preventing a short circuit across the switch-arm in the contact of the switch-arm with separate terminals. As the function and operation of these impedance-coils are well understood as used in this connection, it is not deemed necessary to go into a detailed description thereof here. 85

The operation of the system shown in Fig. 2 is substantially the same as that described 90 with relation to Fig. 1—that is, varying pressure in the secondary will so regulate the energy in the solenoid that the switch B' is caused to move in one direction by said solenoid and in the opposite direction by the spring B'' to cut in or cut out certain steps of the 95 secondary winding. The solenoid N (shown in Fig. 2) may be energized by the current flowing in the lamp-circuit alone or by a combination of the current flowing in the lamp- 100 circuit together with a current derived by a pressure connection to either the primary or secondary windings of the transformer in a variety of ways.

Another method of carrying out our invention 105 is illustrated on the third sheet of the drawings, in which the sections of the secondary are turned against themselves to neutralize each other, which neutralization when removed cuts in the various sections in succession and so builds up the pressure in the external secondary circuit. 110

In Fig. 3 we have illustrated a scheme in which there are seven sections in the secondary, three of which may be reversed, a switch 115 being used which is composed of three independent switches X , Y , and Z , connected in series, and a single switch-tongue coöperating therewith. When the secondary circuit is under full pressure, the switch-tongue is in 120 the position shown in this figure. The current then enters plate 19 of switch Z , passing to plate 17^b via portion 18, then to plate 16 and through the section of the secondary coil back to plate 15 and via member 14 to plate 125 13, from which it passes through wire 20 to plate 19 of switch Y , thence to plate 17^b , through member 18 on the switch-tongue, 130 through the coil-section of the secondary controlled by switch Y , and back again to plate 15, and thence through member 14 to plate 13, and finally through the switch X and coil controlled by it, and then through the solenoid to the lamp-circuit and the four remain-

ing coils of the secondary. Should the resistance in the arc-lighting circuit be reduced, the switch-arm is automatically moved until the contact members 14 and 18 rest on the 5 plates 15^a and 17^a of switch Z. The current then traces the following path, viz: plate 19, member 18, plate 17^a, resistance r' , from plate 17 to plate 15, through the coil of the secondary controlled by switch Z, back to plate 16, through resistance r and plate 15^a, through 10 member 14 and plate 13 and via wire 20 to the remaining switches, coils, or circuits, as before. The resistances r and r' are sufficient of themselves to neutralize the effects 15 of a portion of the secondary windings and compensate for the reduced resistance in the lighting - circuit. Another position of the switch is where each contact member on the arm engages two terminals at once—that is 20 to say, referring to switch Z, when the contact member 14 bears on plates 15 and 15^a at the same time and member 18 similarly bears on plates 17^a and 17^b. In this position the coil controlled by switch Z is practically cut 25 out—that is, the resistance r prevents a complete short circuit in said coil. At the same time the bridge-wire from plate 15 to plate 17, plate 17, resistance r' , plate 17^a, member 18, and the bridge-wire from 17^b to 16 offer a sec- 30 ond path for the short circuit and a current from the secondary coil. The current entering and passing through plate 19 passes to 17^a, through resistance r' to plate 15, and then to plate 13 and on to switches Y and Z and 35 the other circuits, as before described. When the switch-arm is resting on the terminals 17 and 19 and 13 and 16, it is in the starting or neutral position, in which the current passes through the following parts in the order given: 40 19 18 17 15, the coil controlled by the switch, 16 13 20, and the switches Y and X. In this position it will be noticed that the resistances are cut out of the secondary circuit, the two short-circuited paths for the coil are removed, 45 and the current passes through the coil in a reversed direction, which causes a neutralization of one of the remaining coils of the secondary, so that when the switch-arm is in similar terminals of the switches Y and X the 50 secondary electromotive force is practically zero and no current would flow were it not for the effective section in the secondary winding. The switches Y and X operate similarly to switch Z, and the switches come into action 55 one after the other, so that the internal and external circuits are gradually built up or reduced, according to requirements.

According to the system shown in Fig. 3, wherein seven sections are employed in the 60 secondary, three of them being controlled by switches, the reversal of one of these sections under normal running conditions is equivalent to cutting out two sections, the reversal of two of said sections is equivalent to cutting out four sections, and the reversal of 65 three is equivalent to cutting out six sections, the seventh being provided to prevent short

circuit in the secondary. It is obvious that in all of these systems a choking-coil may be connected in series with the arc-lamp circuit, 70 as shown at I" in Fig. 2.

We are aware that many minor changes in the arrangement, construction, and combination of several parts of our system can be made and substituted without in the least departing 75 from the nature and principle of our invention.

Having thus described our invention, what we claim, and desire to secure by Letters Patent, is—

1. The combination with a constant-potential transformer and its circuits, one of said circuits being an auxiliary circuit of constant potential, and another a circuit of varying potential with constant current, said transformer having independent primary and secondary windings, of a source of supply for said transformer in the form of an alternating or pulsating current, a switch or switches in a circuit or circuits of said transformer, and automatic regulating means for controlling said switch or switches, which means is electrically energized by the auxiliary constant-potential circuit and the circuit of varying potential with constant current; substantially as described. 85

2. The combination with a constant-potential transformer and its circuits, one of said circuits being an auxiliary circuit of constant potential, and another a circuit of varying potential with constant current, said transformer having independent primary and secondary windings, of a source of supply for said transformer in the form of an alternating or pulsating current, a switch or switches 100 in a circuit or circuits of said transformer, and automatic regulating means for controlling said switch or switches in either direction, which means is electrically energized by the auxiliary constant-potential circuit and 105 the circuit of varying potential with constant current; substantially as described. 110

3. The combination with a constant-potential transformer and its circuits, one of said circuits being an auxiliary circuit of constant potential, and another a circuit of varying potential with constant current, said transformer having independent primary and secondary windings, of a source of supply for said transformer in the form of an alternating or pulsating current, a switch or switches 115 in a circuit or circuits of said transformer, solenoids which are separately energized by the auxiliary constant-potential circuit, and the circuit of varying potential with constant 120 current, for operating said switch or switches, whereby preponderating pressure in either of the circuits will cause one of the solenoids to dominate the other and throw the switch in the proper direction to establish equilibrium; 125 substantially as described. 130

4. The combination with a constant-potential transformer and its circuits, one of said circuits being an auxiliary circuit of constant po-

tential, and another a circuit of varying potential with constant current, said transformer having independent primary and secondary windings, of a source of supply for said transformer in the form of an alternating or pulsating current, a switch or switches in a circuit or circuits of said transformer, solenoids which are opposed to each other, and which are separately energized by the auxiliary constant-potential circuit, and the circuit of varying potential with constant current, for operating said switch or switches, whereby preponderating pressure in either of the circuits will cause one of the solenoids to dominate the other and throw the switch in the proper direction to establish equilibrium; substantially as described.

5. The combination with a constant-potential transformer and its circuits, one of said circuits being an auxiliary circuit of constant potential, and another a circuit of varying potential with constant current, said transformer having independent primary and secondary windings, of a source of supply for said transformer in the form of an alternating or pulsating current, of a switch for regulating the effective portions of said transformer, positive mechanical means for operating said switch, and solenoids which are energized by the circuits of the system for causing said positive mechanical means to move the switch in different directions or permit the switch to remain stationary; substantially as described.

6. The combination with a constant-potential transformer and its circuits, one of said circuits being an auxiliary circuit of constant potential, and another a circuit of varying potential with constant current, said transformer having independent primary and secondary windings, of a source of supply for said transformer in the form of an alternating or pulsating current, of a switch for regulating the effective portions of said transformer, mechanism normally in position to throw said switch, and solenoids energized by the circuits of the system rendering said mechanism operative with respect to said switch; substantially as described.

7. The combination with a constant-potential transformer and its circuits, one of said circuits being an auxiliary circuit of constant potential, and another a circuit of varying potential with constant current, said transformer having independent primary and secondary windings, of a source of supply for said transformer in the form of an alternating or pulsating current, of a switch for regulating the effective portions of said transformer, mechanism normally in position to throw said switch, and solenoids energized by the circuits of the system rendering said mechanism operative with respect to said switch and variably adjusting the speed of the switch in either direction it may be moved; substantially as described.

8. The combination with a constant-potential transformer and its circuits, one of said

circuits being an auxiliary circuit of constant potential, and another a circuit of varying potential with constant current, said transformer having independent primary and secondary windings, of a source of supply for said transformer in the form of an alternating or pulsating current, a switch for regulating the effective portions of said transformer, mechanism for throwing the switch, solenoids which are energized by the circuits of the system for causing said mechanism to engage with or be disengaged from the switch, and means for limiting the movement of said switch and throwing the same out of engagement with said mechanism; substantially as described.

9. The combination with a constant-potential transformer and its circuits, one of said circuits being an auxiliary circuit of constant potential, and another a circuit of varying potential with constant current, said transformer having independent primary and secondary windings, of a source of supply for said transformer in the form of an alternating or pulsating current, of a switch for regulating the effective portions of said transformer, mechanism for moving said switch in either direction, solenoids which are energized by the circuits of the system to cause the engagement of said mechanism with said switch to move the same in either direction, depending upon the preponderance of strength in either of said solenoids, and means for rendering said mechanism inoperative with respect to said switch when the limit of movement is reached at either extreme; substantially as described.

10. The combination with a constant-potential transformer and the source of supply therefor in the form of an alternating or pulsating current, of a switch for regulating the effective portions of said transformer, a gear attached to said switch, a pinion meshing with said gear, a friction-wheel mounted on the pinion-shaft, a disk with which said friction-wheel engages, means for rotating said disk, and solenoids which are energized by the system, and which exert their energy to cause a relative movement between said friction-wheel and disk, so that the pinion will operate its meshed gear, and throw the switch in one direction or the other; substantially as described.

11. The combination with a constant-potential transformer and its circuits, one of said circuits being an auxiliary circuit of constant potential, and another a circuit of varying potential with constant current, said transformer having independent primary and secondary windings, of a source of supply for said transformer in the form of an alternating or pulsating current, of a switch for cutting in or cutting out sections of the primary or secondary windings of said transformer, and automatic regulating means for controlling said switch, which means is electrically energized by the auxiliary constant-potential

circuit and the circuit of varying potential with constant current; substantially as described.

12. The combination with a constant-potential transformer and the source of supply therefor in the form of an alternating or pulsating current, of a switch for cutting in, cutting out, or reversing the sections of the secondary winding of said transformer, and automatic regulating means for controlling said switch, which means is electrically energized by the system.

13. The combination with a constant-potential transformer and its circuits, one of said circuits being an auxiliary circuit of constant potential, and another a circuit of varying potential with constant current, said transformer having independent primary and secondary windings, of a source of supply for said transformer in the form of an alternating or pulsating current, of a switch for cutting in or cutting out sections of the primary winding of said transformer, and automatic regulating means for controlling said switch, which means is electrically energized by the auxiliary constant-potential circuit and the circuit of varying potential with constant current, substantially as described.

14. The combination with a constant-potential transformer and its circuits, one of said circuits being an auxiliary circuit of constant potential, and another a circuit of varying potential with constant current, said transformer having independent primary and secondary windings, of a source of supply for said transformer in the form of an alternating or pulsating current, of a switch for controlling the effective portions of said transformer, automatic regulating means for controlling said switch, which means is electrically energized by the auxiliary constant-potential circuit and the circuit of varying potential with constant current, and shunt or parallel impedance-coils around each translating device in the circuit; substantially as described.

15. The combination with a constant-potential transformer and its circuits, one of said circuits being an auxiliary circuit of constant potential, and another a circuit of varying potential with constant current, said transformer having independent primary and secondary windings, of a source of supply for said transformer in the form of an alternating or pulsating current, of a switch for controlling the relations of the portions of said transformer to each other, automatic regulating means for controlling said switch, which means is electrically energized by the several circuits of the system, shunt or parallel impedance-coils around each translating device in the system, and an impedance-coil "I" in series with the circuit of varying potential with constant current; substantially as described.

tial transformer and its circuits, one of said circuits being an auxiliary circuit of constant potential, and another a circuit of varying potential with constant current, said transformer having independent primary and secondary windings, of a source of supply for said transformer in the form of an alternating or pulsating current, of a switch for controlling the relations of the portions of said transformer to each other, automatic regulating means for controlling said switch, which means is electrically energized by the several circuits of the system, shunt or parallel impedance-coils around each translating device in the system, and an impedance-coil "I" in series with the circuit of varying potential with constant current; substantially as described.

16. The combination with a constant-potential transformer and its circuits, one of said circuits being an auxiliary circuit of constant potential, and another a circuit of varying potential with constant current, said transformer having independent primary and secondary windings, of a source of supply for said transformer in the form of an alternating or pulsating current, said secondary windings being arranged in sections, of a switch-arm coöperating with the terminals of said sections, resistance or impedance coils which are cut in or out by said switch-arm for increasing or decreasing the effectiveness of said sections, whereby one or more of said sections are partially or wholly neutralized by said resistance, and means energized by the auxiliary constant-potential circuit and the circuit of varying potential with constant current for automatically operating said switch; substantially as described.

In testimony whereof we hereunto affix our signatures, in the presence of two witnesses, this 25th day of February, 1899.

WALDO A. LAYMAN.
FERDINAND SCHWEDTMANN.
